UNITED STATES PATENT OFFICE.

JAMES E. FARWELL, OF WORCESTER, MASSACHUSETTS.

DESIGN FOR A CHECK.

SPECIFICATION forming part of Design No. 27,251, dated June 29, 1897.

Application filed April 24, 1897. Serial No. 633,803. Term of patent 7 years.

To all whom it may concern:

Be it known that I, JAMES E. FARWELL, a citizen of the United States, residing at Worcester, in the county of Worcester and State of Massachusetts, have invented a new and useful Design for Checks, of which the following is a specification.

The particular object of this present invention has been to produce a new, useful, and graceful form of check which is especially useful as an identification-check.

The particular design herein shown and claimed comprises a check characterized by having oppositely-disposed T-shaped slots or grooves in the ends thereof and by having the sides and ends gracefully curved, as herein further described.

Referring to the drawing accompanying this specification and forming part of this application, the figure represents an elevation of my design for a check.

In detail, A represents the check.

The sides B B of the design are formed on concave lines, and the upper and lower ends of the check have oppositely-disposed T-shaped slots or grooves t t cut therein.

The ends of the check are convexly rounded,

as at a a a a, to the mouth of the T-shaped grooves, and the narrow mouths of the T-shaped grooves are rounded, as at d d d d. 30 As thus shaped the check has a very pleasing appearance to the eye.

The check thus shaped may be snapped onto a suspender by forcing the suspender into both of the T-shaped grooves t t, and in that 35 way may be held and kept by the possessor.

Checks of my design are intended to be suitably engraved, so that the possessor may be identified as a member of various organizations or fraternities, or the name and address of the possessor may simply be engraved thereon to identify his person in case of accident.

What I claim, and desire to secure by Letters Patent, is—

The design for a check, substantially as herein shown and described.

In testimony whereof I have hereunto set my hand in the presence of two subscribing witnesses.

JAMES E. FARWELL.

Witnesses:
